(57) **CLAIM**

I claim the ornamental design for a pan rack tray support, as shown and described.

DESCRIPTION

FIG. 1 shows a perspective view of the pan rack tray support.

FIG. 2 shows a top plan view thereof.

FIG. 3 shows a bottom plan view thereof.

FIG. 4 shows a front elevation view thereof.

FIG. 5 shows a rear elevation view thereof.

FIG. 6 shows a right side elevation view thereof.

FIG. 7 shows a left side elevation view thereof.

FIG. 8 shows a perspective view of the pan rack tray support as used in its environment.

FIG. 9 shows a perspective view of an alternative embodiment of the pan rack tray support.

FIG. 10 shows a top plan view of the alternative embodiment.

FIG. 11 shows a bottom plan view of the alternative embodiment.

FIG. 12 shows a front elevation view of the alternative embodiment.

FIG. 13 shows a rear elevation view of the alternative embodiment.

FIG. 14 shows a right side elevation view of the alternative embodiment.

FIG. 15 shows a left side elevation view of the alternative embodiment; and,

FIG. 16 shows a perspective view of the alternative embodiment of the pan rack tray support as used in its environment.
